UNITED STATES PATENT OFFICE.

JOHN E. UNGER, OF NEW YORK, N. Y., ASSIGNOR TO JACQUES LEVY, OF SAME PLACE.

PORTABLE FARADIC BATTERY.

SPECIFICATION forming part of Letters Patent No. 556,708, dated March 17, 1896.

Application filed February 6, 1896. Serial No. 578,243. (No model.)

To all whom it may concern:

Be it known that I, JOHN E. UNGER, a citizen of the Kingdom of Sweden, residing at New York, in the city, county, and State of New York, have invented certain new and useful Improvements in Portable Faradic Batteries, of which the following is a specification.

This invention relates to an improved portable faradic battery of that class known as "pocket-batteries" for physicians' and surgeons' use. Generally these devices consist of a portable casing containing a galvanic battery and an induction-coil adapted for use with various electrodes for applying the induction currents to different parts of the human body.

In my invention the exterior casing of the battery forms the electrodes and serves as an enclosure for a so-called "dry battery" and the induction-coil, so that the battery can either be held by both ends in the hands or held at one end in one hand, while the remaining part is applied by means of a sponge or other electrode to the part of the body to be treated, whereby the entire battery is made more compact and better adapted for external application, and the invention consists of a portable battery which comprises a tubular central portion of non-conducting material, a sheet-metal casing fixed to said central portion and within which a suitable dry battery is placed, an induction-coil arranged on the core supported by the tubular central portion, a sliding casing inclosing said induction-coil and provided with a tubular portion extending over the core of the induction-coil and being guided on the central portion, contact devices between the battery and the induction-coil, a vibrator connected in the usual manner with said induction-coil, and a switch device by which the induction-currents are conducted to the fixed and sliding portions of the casing so that they can be used as electrodes, as will be hereinafter described and finally pointed out in the claims.

In the accompanying drawings, Figure 1 represents a side elevation of my improved portable faradic battery. Fig. 2 is a longitudinal section of the same. Fig. 3 is a transverse section on line 3 3, Fig. 2; and Fig. 4 is

a transverse section on line 4 4 of the same figure.

Similar letters of reference indicate corresponding parts.

Referring to the drawings, A represents the tubular central portion or main body of my improved portable faradic battery, which is made of hard rubber or other non-conductor of electricity and is reduced between its shouldered ends d d'. In the center of the central tubular portion A the core C of the induction-coil is arranged, it being entirely surrounded by the central portion A, as shown in Fig. 2.

On the reduced portion a of the tubular portion surrounding the core C are arranged the usual primary and secondary windings of the induction-coil D, which are retained between the shoulders d d' at the inner and outer ends of said tubular portion. The induction-coil is inclosed by a sliding sheet-metal casing E, which is guided by a longitudinal slot e therein on a headed screw or pin e' attached to the shoulder d' of the central portion A. The end of the metallic sliding casing E is made with a hollow knob e², so as to form connection with an electrode, if one is to be used in connection with the faradic battery. For ordinary purposes the sliding casing forms one electrode of my improved battery. At the interior of the sliding casing E is fixed a brass tube E', which fits over the core C when inserted into the induction-coil and which serves as a damper to uncover the induction-coil more or less, so that induction-currents of increased or decreased strength are conducted through the body. The more the casing is drawn out the more the core is uncovered by the damper-tube and the greater will be the strength of the induction-currents generated.

To the tubular central portion A is fixed a second casing E², which is applied thereto by suitable fastening-screws E³, and in which a suitable dry battery F, of any approved construction, is centered by arming it with circumferential bands f having radial steady-pins f', as shown in Fig. 2. The outer portion or body of the dry battery is connected by the bands and pins with the casing E², while the carbon element thereof is connected

5 by a center pin f^2 with a contact-spring g attached to the hollow portion A' of the central portion A , said contact-spring being electrically connected with the primary winding 5 of the induction-coil D . The outer end of the stationary casing E^2 is likewise provided with a perforated knob E^X for inserting therein connecting-wires of a suitable electrode in case the battery is to be used with separate 10 electrodes.

15 The secondary winding is connected with a metallic block h attached to the interior hollow portion A' of the tubular central portion A , said metallic contact-block being in turn connected by a switch-screw H with the fixed casing E^2 when the screw is turned inward sufficiently, so that its head forms contact with the casing E^2 . As soon as this is 20 accomplished, the induction-coil operates in connection with the vibrator V in the usual manner, said vibrator being arranged in the hollow portion A' of the tubular central portion A , as shown in Fig. 2, and formed of a vibrating contact-spring and a stop-screw, as 25 is customary in induction-coils.

30 The connection of the secondary winding with the sliding casing or electrode is made by a contact-spring S that is connected with the secondary winding and applied to the non-conducting shoulder d' of the central portion A , said spring being always in contact with the casing E , whether the same is in normal or drawn-out position. When, therefore, the 35 switch-screw H is turned in sufficiently so as to form contact with the casing E^2 , the circuit is closed and the induction-coil operated by the battery F . By drawing the casing E out more or less the induction-current is increased and can be regulated as required by adjusting 40 the casing E on the induction-coil. By removing the casing E sponges, brushes, or other electrodes can be applied to the induction-coil whenever special application to the body is made, the faradic battery being then 45 held by the casing E^2 , which forms the other electrode.

50 The advantages of my improved faradic or pocket battery are, first, that the same can be made in sizes which will answer all the requirements of the larger portable induction-coils heretofore used; secondly, that by using a dry battery no spilling of acid is caused, while the new battery can be replaced with the greatest ease at any time when the old 55 battery has run out, and, thirdly, the battery is

quickly put into action so as to be quickly applied to any part of the body.

Having thus described my invention, I claim as new and desire to secure by Letters Patent—

60 1. A portable faradic battery, consisting of a tubular central portion formed of non-conducting material, an induction-coil arranged on said central portion, a sliding casing or electrode guided on the induction-coil and provided with an interior non-conducting damper-tube passing over the core of the induction-coil, a casing fixed to said tubular central portion, a battery in said casing electrically connected with the primary winding 65 of the induction-coil, a vibrator connected with said primary winding, and a switch connecting the secondary winding of the induction-coil with the sliding and fixed casings or electrodes, substantially as set forth. 70

75 2. The combination, with a tubular central portion of non-conducting material, an induction-coil applied to the same, a casing fixed to the said central portion, a battery located in the same and electrically connected with 80 said fixed casing, electrical connection between the carbon element of the battery and the induction-coil, a vibrator, and a switch for starting and interrupting the induction-coil, substantially as set forth. 85

90 3. The combination of a central tubular portion of non-conducting material, a soft-iron core arranged in the center of said tubular portion, an induction-coil arranged on the said central portion, a sliding casing or electrode guided on said induction-coil and placed in contact with the secondary winding of the same, a second casing or electrode fixed to the opposite end of the central tubular portion, a battery placed in said casing and electrically connected with the same, means for connecting the carbon pole of the battery with the induction-coil, and a switch connecting the fixed casing with the secondary 95 winding of the induction-coil so as to induce 100 the induction-current to the same, substantially as set forth.

In testimony that I claim the foregoing as my invention I have signed my name in presence of two subscribing witnesses.

JOIN E. UNGER.
